UNITED STATES PATENT OFFICE.

ARTHUR FARRAR AND WILLIAM P. ELLIOTT, OF CHICAGO, ILLINOIS.

AUTOMATIC LOCK FOR GATES.

SPECIFICATION forming part of Letters Patent No. 355,518, dated January 4, 1887.

Application filed September 27, 1886. Serial No. 214,596. (No model.)

To all whom it may concern:

Be it known that we, ARTHUR FARRAR and WILLIAM P. ELLIOTT, citizens of the United States, residing at Chicago, in the county of Cook and State of Illinois, have invented a certain new and useful Improvement in Automatic Locks for Gates; and we hereby declare the following to be a full, clear, and exact description of the same.

Our improvement relates, particularly, to a lock for use on gates of the class of that for which an application for Letters Patent of the United States, Serial No. 201,354, was filed May 6, 1886, by Mortimer B. Mills.

It is our object to provide automatically-operating means whereby the gate-bars shall be locked both in their raised and lowered conditions, but particularly when raised, to prevent their unintentional closing by the effect of wind.

Our invention consists in providing a gate the bar of which is actuated by a piston-and-cylinder mechanism, with a lock engaging automatically with the piston portion of the mechanism to hold the bar in its raised or lowered position, and released from such engagement by pneumatic force exerted independently of such piston portion through suitable means.

Our invention also consists in certain details of construction and combinations of parts, all as hereinafter more fully set forth.

In the drawings, Figure 1 represents our improvement applied to a pneumatic gate, of which only one hollow post is shown in sectional elevation, containing the bar-actuating mechanism, the swinging bar being broken away at opposite ends. Fig. 2 shows a part of our improved locking device enlarged in sectional elevation, and Fig. 3 is an enlarged perspective view of the other part of the locking device, shown as engaging with the cross-piece of a frame with which the piston-rod is connected.

Our improvement may of course be applied for the accomplishment of its purpose to various forms of gates of the class referred to, though to illustrate its operation we show and describe it in connection with the gate hereinbefore mentioned as forming the subject of a pending application for Letters Patent, and the gate being fully shown and described in

the said application, and as it forms no part of our invention, only so much of it is shown in the present connection as will render clear the operation of our improved attachment, with a description of the operation of the gate, which is as follows: Although but one gate-bar, A, is shown pivotally supported to swing in a vertical plane upon a preferably hollow post, B, the barrier is ordinarily formed by two such posts carrying pivotal arms connected to be raised simultaneously and lowered simultaneously by the raising or lowering of one bar. The manner of connection of the bars for the foregoing purpose is indicated in Fig. 1 of the drawings, and involves a practically endless chain, C, passing around and secured upon a wheel, C', or segmental portion of a wheel upon the axis of one gate-bar, and thence through a conduit, D, into the other post (not shown) and around a similar bearing upon the axis of the opposite gate-bar. (Also not shown.) This manner of connection between the two gate-bars, however, is not essential to the application of our improved locking device, as will be readily understood from the following description, but is only illustrated and described for the sake of convenience, as our improvement may be employed where the bars are connected differently from the manner shown for simultaneous action—say both to be actuated directly by fluid-pressure, or where a single swinging bar forms the barrier, or where two bars are not connected for simultaneous action, by a single operation of the pump.

Within the post B, supported at opposite sides of the axis of the bar A, are the cylinders D and D', containing pistons E and E', having their rods F and F' secured at their lower ends to the lower cross-heads, r and r', of frames G and G' movable in guides on the cylinders longitudinally of the same, the frames forming connecting links on opposite sides of the axis of the bar A in the chain C.

The cylinders communicate from their upper ends, through pipes q and q', with a suitable fluid-pump, (not shown, but of common construction,) communication being opened between the pump and one cylinder and simultaneously closed between the pump and the other cylinder, at the same time presenting an escape-outlet for the contents of the last-

named cylinder by means of a suitable three-way cock, (not shown, but also of old construction.) Thus, as shown, the bar A has been lowered by the introduction of pressure 5 into the cylinder D upon the piston E, producing the simultaneous rise of the piston E', from above which the fluid contents of the cylinder D' have escaped through the exhaust in the three-way cock referred to, and the bar 10 will be raised by introducing pressure from the pump upon the piston E', whereby the piston E will be actuated as was the piston E' in lowering the bar.

When raised, particularly, it is desirable to 15 lock the bar in its raised position, which we accomplish by means of the device forming our improvement, and comprising a chamber, H', suitably supported, and communicating by a pipe, p, with the pipe q of the cylinder 20 D, containing the piston which lowers the bar. The chamber H' is provided internally with an air-tight flexible diaphragm, I, which covers the communication of the chamber with the pipe p, and the diaphragm supports a 25 broad bearing, o, carrying a vertical standard or link, n', which extends through a guide-extension, m', leading from the upper side of the chamber H'.

K' is a bell-crank lever, pivoted at its angle 30 in a suitable bearing, l', inside the post, and pivotally connected at one end, as shown in Fig. 3, of the lever K and link or standard n', with the end of the link or standard n'; and the opposite end of the lever K' is notched to form 35 a catch or latch, L', normally in the path of the cross-head r' of the frame G'.

With the piston E' in the position shown, to 40 which it is moved by lowering the bar A, with the introduction of pressure into the cylinder

D upon the piston E, as aforesaid, the fluid 45 contents have been exhausted from the cylinder D', pipes q' and p, and chamber H, and the diaphragm I in the chamber H is in its normal condition, (shown in Fig. 2,) which maintains the latch L in the path of the cross-head r, whereby, when the latter is lowered, as shown, to lower the bar A, it will be engaged by the latch L, as illustrated, which will hold it and, until released, prevent the raising 50 of the bar. When there are two cylinders, as represented, and operating as described, this release is accomplished by introduction of the fluid-pressure into the cylinder D' through the pipe q', whence it also enters the chamber H 55 through the pipe p underneath the diaphragm I, expanding the same, and, as a consequence, raising the link p and turning the bell-crank lever to disengage the latch L from the cross-head r.

60 Two locking devices may be employed, as shown in Fig. 1, one being the exact counterpart of the other, the one for holding the bar or bars when lowered to form the barrier, as already described, and the other to hold it or them when raised to remove the barrier.

The parts of the locking device shown at the right of Fig. 1 are distinguished from those

shown at the left by means of primes applied to the letters which indicate the corresponding parts in each. As the pipes which lead 70 respectively to the chambers H and H' cross each other, that leading to the chamber H is marked p' and that which leads to the chamber H' is marked p.

The operation of the lock in holding the 75 gate-bar when down having already been fully described, the simultaneous operations of both locks will be understood from the following description of the operation of the lock for holding the gate-bar when up, which, as hereinbefore stated, is the more important object 80 of our invention.

Pressure is introduced into the cylinder D' to raise the bar from its lowered position while the piston E is being held in its lowered position 85 by the adjacent latch L, and by the introduction of such pressure into the cylinder D' the same, or rather a portion of the same, is also introduced into the chamber H, against the under side of the diaphragm I, controlling the 90 latch L, which, when the gate-bar is down, holds the piston E. The pressure expands the diaphragm I and effects the release of the piston E, which thereupon is permitted to rise with the descent of the piston E', the rod of 95 which, on passing the latch L' in its path, will be held till released in the manner already described of releasing the rod of the piston E.

It will be understood, as already less definitely stated, that with the introduction of the 100 pressure into the cylinder D' and chamber H' connected with it the fluid contents are exhausted from the cylinder D and chamber H connected with it, whereby the diaphragm I' assumes its normal position and the latch L' is 105 in the path of the cross-head r'.

It will thus be seen that the normal position of each latch L and L' is in the path of a piston rod or frame, with which it engages by an operation resembling a spring-catch, and that 110 to release it requires the pressure used to move the bar from one position to the other, and the exercise of that pressure simultaneously with or before the movement of the piston which actuates the bar to move from a previous position in which it is being held by the locking device.

It is found in practice that the diaphragms being large and the resistance slight they are affected by the pressure underneath them more 120 readily than the pistons; hence they release the latches before the gate-bars move.

What we claim as new, and desire to secure by Letters Patent, is—

1. The combination, with a gate having its 125 swinging bar actuated pneumatically by a piston-and-cylinder mechanism, of a lock engaging automatically with the piston portion of the mechanism, and means, substantially as described, for releasing the lock from such engagement by pneumatic force exerted independently of said piston portion, substantially 130 as and for the purpose set forth.

2. The combination, with a gate having a

swinging bar connected with pistons on opposite sides of the axis of the bar and actuated in cylinders by air-pressure simultaneously in opposite directions, of locks for the pistons, 5 normally in condition to engage with the piston-rods, and means, substantially as described, for alternately releasing the locks by air-pressure exerted independently of said pistons, substantially as and for the purpose set forth.

10 3. The combination, with a gate having a swinging bar connected with pistons on opposite sides of the axis of the bar and actuated in cylinders by air-pressure simultaneously in opposite directions, of a lock comprising a 15 pivotally-supported lever having a latch near one extremity normally in position to engage with the rod of one piston, a chamber communicating with the compressed-air conduit leading to the other piston and covered by a flexible diaphragm carrying a standard, to which the opposite end of the lever is pivotally con-

nected, substantially as and for the purpose set forth.

4. The combination, with a gate having a swinging bar connected with pistons on opposite sides of the axis of the bar and actuated in cylinders by air-pressure simultaneously in opposite directions, of locks for the pistons, each lock comprising a pivotally-supported lever, K, having a latch, L, near one extremity 20 normally in position to engage with a rod of one piston, a chamber, H, communicating with the compressed-air conduit leading to the other piston and covered by a flexible diaphragm, I, carrying a standard, n, to which the opposite 25 end of the lever is pivotally connected, substantially as and for the purpose set forth.

ARTHUR FARRAR.

WILLIAM P. ELLIOTT.

In presence of—

J. W. DYRENFORTH,

GEORGE C. COOK.
